POT TYPE LIQUID FUEL BURNER FOR
UNIT HEATERS

George R. Neumann, St. Clair Shores, Eugene F. Farrell, Grosse Pointe Woods, and Edward J. Effinger, Ferndale, Mich., assignors to Borg-Warner Corporation, Chicago, Ill., a corporation of Illinois

Application January 11, 1946, Serial No. 640,536

2 Claims. (Cl. 158—91)

1

The present invention relates to unit heaters, and has more particular reference to a burner construction for heaters for burning liquid fuel.

One of the principal objects of this invention is to simplify the construction of a liquid fuel burner such as contemplated herein, and to improve the efficiency, operation and dependability of such a burner.

Another principal object is to provide an arrangement for burning liquid fuel wherein an auxiliary air supply in addition to the primary air, is injected directly into the gases in the upper region of a vaporizing chamber.

Still another principal object hereof is to provide a pilot flame baffle arrangement for effecting a more complete ignition of the vaporized gases as they leave the vaporizing chamber and enter the combustion chamber.

Another object is to provide an auxiliary air supply passageway in the upper region of the vaporizing chamber of an oil burning unit which passageway is so arranged that it provides a pilot flame baffle directly across the vaporizing chamber and which effects a control of the direction of movement of vaporized gases into the combustion chamber. The present arrangement is such that it supplies such gases with heated extraneous air for increasing combustion thereof.

Another object is to provide a plurality of air jets that are adapted to supply heated atmospheric air, (from outside the heater) to the central region of the liquid fuel bowl or basin of an oil burner, thus to prevent accumulation and "cracking" of any considerable volume of stagnant rich gases which may result in the formation of carbon.

Additional objects, aims and advantages of the invention contemplated herein will be apparent to persons skilled in the art after the construction and operation of the arrangement is understood from the within description.

It is preferred to accomplish the numerous objects hereof and to practice the invention in substantially the manner hereinafter fully described, and as more particularly pointed out in the appended claims. Reference is now made to the accompanying drawings that form a part hereof, in which:

Fig. 1 is a top plan of a unit heater showing the present improvements therein;

Fig. 2 is a vertical transverse section of the structure shown in Fig. 1;

Fig. 3 is a central vertical section of the burner assembly, the view being taken along line 3—3 on Fig. 5;

Fig. 4 is a top plan of the burner assembly, the view being along line 4—4 on Fig. 5 and partly broken away; and

Fig. 5 is a vertical longitudinal section of the burner assembly when taken along line 5—5 on Fig. 4.

The drawings are to be understood as being more or less of a schematic character for the purpose of disclosing a typical or preferred embodiment of the improvements contemplated herein, and in these drawings like reference characters identify the same parts in the different views.

Referring first to Figs. 1 and 2, the unit heater or heat exchanger 10 comprises a cabinet formed of a plurality of vertical walls 11, 11 arranged to provide a hollow rectangular cabinet that is closed by a top wall 12. In the lower region of the cabinet there is a horizontal partition 13 dividing the interior of the cabinet into a large upper compartment A and a smaller lower compartment B. This partition has an elongated opening 14, and there is an elongated opening 15 toward the rear of the partition. The top plate or wall 12 is provided with an elongated opening 16 above partition opening 15 and an air circulating tube 17 extends between and connects these rectangular openings. A flue connection or outlet collar 18 surrounds an opening in the back wall of the cabinet for discharge of the products of combustion to the chimney. As seen in Fig. 2, the base of the cabinet has a plurality of feet 19 that support it above the floor in order to permit air to enter beneath the walls 11. This air is adapted to circulate around a heater unit in the lower compartment B where it is preheated and then passes up through the air circulating tube 17 as indicated by the arrows, where it is further raised in temperature and discharges through opening 16 into the space being heated.

The burner assembly, designated generally as 20, is mounted in a pendant manner on the front portion of the partition 13 with its cylindrical combustion chambers aligned with the opening 14 in said partition. This burner assembly is shown in detail in Figs. 3, 4 and 5. The burner preferably comprises a basin-like vaporizing chamber having a downwardly bowed bottom plate 21 and an upstanding annular wall 22. In the upper re-

gion of an annular wall 22 there is a plurality of apertures 23 which supply primary combustion air to the vaporizing chamber. A cover plate 24 extends across the top of the vaporizing chamber and is secured thereto by seaming the margins of said cover plate and upstanding walls as at 25.

Liquid fuel is supplied to the basin through a pipe connection 26, the flow of this fuel being controlled by a metering valve 26a so that a small pool or puddle of liquid fuel is maintained in the bottom of the basin. The closure plate 24 has spaced circular openings in it, and cylindrical combustion chamber walls 27 are secured in these openings by beading and flanging said cylindrical walls around the edges of the openings as at 28. The upper portions of the cylindrical walls are flanged as at 29 and are secured by welding or otherwise to a plate 30 which in turn is welded or otherwise secured to the partition 13 at the opening 14 therein.

The front of the vaporizing chamber has an offset portion 31 as shown clearly in Figs. 3 and 4 which has an opening in its upper portion that is closed by a hinged door 32. This provides suitable means whereby a flame may be inserted into the vaporizing chamber to ignite the pond or puddle of liquid fuel therein. The cylindrical walls 27 of the combustion chambers are of reticulated form, that is preferably made by providing a plurality of small holes 33 therein for admitting secondary combustion air into these chambers for promoting combustion of the gases arising from the vaporizing chamber. These ignited gases or flames pass upward into the chamber A of the cabinet where they continue to burn and circulate around the air tube 17 in the manner shown by the wavy arrows in Fig. 2. The fresh air which has been preheated in chamber B circulates through tube 17 where its temperature is raised to the desired degree by contact with said tube and it then passes out of the cabinet through discharge openings 16. The path of travel of the heated air is indicated by plain arrows.

The pilot flame baffle means C which supplies auxiliary air to the gases or vaporized fuel arising from the puddle in the vaporizing chamber comprises an arrangement having a generally hour-glass shape as seen in Fig. 4. This baffle C is mounted in a plane below the combustion chamber walls 27 and it preferably hangs pendant from the cover plate 24 of the vaporizing chamber. The plane of the horizontal axis of this baffle C is tangent to both the combustion chamber walls 27 and said baffle extends horizontally from front to rear across the vaporizing chamber as seen in Fig. 3.

The baffle C, which is also an auxiliary air device comprises rather short side walls 34 depending in spaced relation to each other from the plate 24, and, as shown in Fig. 4, these walls are horizontally spaced apart and bow or curve inwardly toward each other in long sweeping arcs so as to effect an hour-glass formation in horizontal section. The lower margins of the bowed side walls 34 are joined by a bottom wall 35 and the upper margins of said walls have outward turned flanges 36 (Fig. 4) that are welded or otherwise secured to the under face of plate 24. Small apertures 37 are made in the bowed vertical walls 34 to provide air jets which discharge into the vaporizing chamber in the upper region thereof. These jets of air are close to the entrances to the combustion chamber walls 27 so

that extraneous air is commingled with the combustible gases entering the combustion chamber walls 27 from the vaporizing chamber and thereby materially increase the combustion of said gases. Inlet ports 38 are made in the plate 24 to admit extraneous air into the end regions of the hour-glass passageway formed by the walls of the pilot flame baffle. The air entering the hour-glass passageway becomes heated therein and therefore increases rather than decreases combustion of the burning gases. The arrangement is such that this baffle tends to divide the gases by directing or piloting them toward the inlets to the combustion chambers and thereby prevents stagnation in the circulation of the combustible gases with the resultant formation of carbon.

The structure described above is preferably made of sheet metal. In operation there is a rapid transfer of heat from the burning gases and other products of combustion to the air which is being circulated through the heater so that said air is quickly raised in temperature and is distributed through the top of the circulator tube 17 from which it is discharged into the apartment or other space being heated.

While this invention has been described in detail in a preferred form or embodiment, it will be apparent to persons skilled in the art, after understanding the improvements, that various changes and modifications may be made therein without departing from the spirit or scope thereof. It is aimed in the appended claims to cover all such changes and modifications.

We claim:

1. In a burner assembly for heating devices and the like including a liquid fuel basin-shaped vaporizing chamber having an upstanding side wall arranged to carry a top wall, means arranged to supply liquid fuel to the vaporizing chamber, and spaced combustion chambers having upstanding side walls operatively disposed above the vaporizing chamber and having portions thereof arranged in open communication with portions of the vaporizing chamber, those improvements which comprise a bottom wall and perforate side walls depending from said top wall and defining an auxiliary air supply passageway extending across said vaporizing chamber in the upper regions thereof and between the spaced combustion chambers, the top wall of the vaporizing chamber having inlet ports adjacent the ends of the passageway for admitting extraneous air thereto.

2. In a burner assembly for heating devices, a bottom wall and an upstanding perforate wall defining a liquid fuel vaporizing chamber having a top wall, means arranged to supply liquid fuel to the vaporizing chamber, and spaced combustion chambers having upstanding side walls operatively disposed above the vaporizing chamber and having portions thereof arranged in open communication with portions of the vaporizing chamber, in combination with a bottom wall and perforate side walls depending from said top wall and defining an auxiliary air supply passageway extending across said vaporizing chamber in the upper regions thereof and between the spaced combustion chambers.
